UNITED STATES PATENT OFFICE.

ELNORA IRWIN, OF MONTPELIER, INDIANA.

CHICKEN-BROODER.

1,165,509.

Specification of Letters Patent. Patented Dec. 28, 1915.

Application filed January 30, 1915. Serial No. 5,193.

To all whom it may concern:

Be it known that I, ELNORA IRWIN, citizen of the United States, residing at Montpelier, in the county of Blackford and State of Indiana, have invented certain new and useful Improvements in Chicken-Brooders, of which the following is a specification.

The present invention relates in general to poultry culture, and more particularly to an improved chicken brooder which embodies novel features of construction whereby it can be easily and quickly dismembered and taken apart so as to be readily maintained in a clean and sanitary condition or transported from place to place.

A further object of the invention is to provide a chicken brooder which is comparatively simple and inexpensive in its construction, which can be heated by any ordinary lamp without danger of the smoke or heat injuring the chicks, which can be readily set up in operative position, and which admits of access being readily had to any part of the brooder for cleaning or changing the same.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a front elevation of a chicken brooder constructed in accordance with the invention, the various parts being separated and shown one above the other in the order in which they are placed in position when assembling the brooder for use. Fig. 2 is a longitudinal vertical sectional view through the brooder, and Fig. 3 is a transverse vertical sectional view through the brooder.

Corresponding and like parts are referred to in the following description and indicated in all the views of the drawing by the same reference characters.

Referring to the drawings, the reference character A designates the base or stand upon which the brooder is mounted. This stand is constructed with the four corner legs or standards 1 and a lamp receiving casing 2 which is held in an elevated position thereby. The ends 2^a of the lamp re-

ceiving casing 2 are preferably inclined, as shown more clearly by Fig. 2, while the sides of the lamp inclosing casing are provided toward the bottom thereof with ventilating openings 5.

A lamp supporting plate B which is preferably formed of sheet metal rests removably upon the top of the base A and extends across the upper end of the lamp receiving casing 2. This plate B has a concave formation and is provided at the center thereof with a lamp receiving and supporting pocket 4, the said pocket being pendent from the plate and extending downwardly into the lamp inclosing casing 2. A lamp C of any suitable type, either oil or electric, is placed within the pocket 4 so as to rest upon and be supported by the bottom thereof. Suitable ventilating openings 5 are formed in the sides of the pocket 4 so as to provide for the necessary circulation of air.

The body D of the brooder is next placed in position, the said body having a rectangular shape corresponding to that of the base or stand A. The lower end of the body D telescopes over the upper end of the base A until the corners of the said base are engaged by corner blocks 6 which are applied to the interior of the body D at a point slightly above the lower end thereof. The body of the brooder is thus supported in position and held securely against lateral displacement, a tight joint being at the same time provided between the body D and the base A. The front of the body D may be provided with a transparent window 7 through which the interior of the brooder can be viewed without opening the same, and also with the usual door 8 through which chicks may be placed in the brooder or removed therefrom. It will also be observed that ventilating openings 9 are provided in opposite ends of the body D, the said openings being preferably covered by a screening 10 or like material.

The bottom E of the brooder fits removably within the body D and rests loosely upon the before mentioned corner blocks 6. This bottom includes a rectangular frame 11 which has comparatively coarse wire screening or like perforate material 12 tacked or otherwise secured thereto. An opening is provided in the central portion of the perforate bottom sheet or screening 12, the edges of the opening being reinforced by a

metallic plate 13 and the opening being surrounded by an upwardly projecting ring 14 of screening or like perforate material which serves to prevent the chicks from falling through the opening. A collar 15 of asbestos or like material preferably surrounds the base of the ring 14, and a layer 16 of muslin, cotton fabric or the like rests upon the perforate bottom plate 12 so as to provide a suitable floor for the brooder. The edges of this fabric flooring 16 may be tacked to the frame 11 as indicated at 17, although it will be obvious that this fabric can be readily replaced or renewed whenever such is found necessary. The ring 14 is arranged directly over the lamp receiving pocket 4 and may receive the chimney of the lamp. The concave formation of the lamp supporting plate B permits warm air 20 to filter upwardly through the fabric flooring of the brooder, although direct drafts are avoided.

The top F is next placed in position, the said top including a frame 18 which fits closely within the interior of the body D and has a piece of fabric 19 stretched across the same. This frame rests removably upon cleats or strips 20 which are applied to the interior of the body D toward the top thereof.

The cover G is the last member to be fitted upon the brooder and this member is formed of wood or other similar material so as to provide a backing for the fabric ceiling 19 and shield the same from injury. The edge of the cover G is provided with a peripheral flange 21 which fits around the top of the body D so as to hold the cover securely against lateral displacement and provide a tight joint between the cover and the body.

All of the various members or sections of the brooder are constructed independently of each other and rest removably in position so that they can be readily separated at any time for the purpose of cleaning or moving the brooder. The fabric floor and ceiling can be easily renewed and access can be had to all parts of the brooder for thoroughly cleaning the same. The bottom E must be tilted within the body D of the brooder before it can be lifted above the cleats 20, and a handle 22 is shown as applied to one end of the bottom frame 11. In a somewhat similar manner a finger loop 24 is shown as applied to one end of the ceiling frame 18. This manner of constructing the brooder in sections which rest removably upon each other and at the same time provide the necessary tight joints is very advantageous in that it enables the brooder to be readily packed for shipment or storage, and also admits of access being readily had to all parts of the interior of the brooder for cleaning the same.

Having thus described the invention, what

I claim as new and desire to secure by Letters Patent, is:

1. A brooder including a main casing, a fabric flooring therefor, a lamp receiving casing under the main casing, and a concave lamp supporting plate provided with a dependent lamp receiving pocket and interposed between the main casing and the lamp receiving casing, the concave formation of the plate providing an air space under the fabric flooring so that warm air can filter upwardly through the same.

2. A brooder including a main casing, a perforate floor plate therefor, said floor plate being formed with an opening, an upwardly projecting ring surrounding the opening, fabric flooring resting upon the perforate floor plate, a base, and a concave lamp supporting plate interposed between the base and the main casing, said plate being provided at a point under the opening of the floor plate with a lamp receiving pocket and the concave formation of the plate providing an air space under the perforate floor plate so that warm air can filter upwardly through the same.

3. A brooder including a main casing, a removable floor frame fitted within the main casing, a perforate floor plate applied to the same and having an opening therein, a ring surrounding the opening and projecting upwardly from the perforate floor plate, a fabric flooring resting upon the perforate floor plate, a supporting stand upon which the main casing rests, said supporting stand being formed with a lamp inclosing casing, and a concave lamp supporting plate interposed between the supporting stand and the main casing and provided at a point under the opening of the perforate floor plate with a lamp receiving pocket, the concave formation of the plate providing an air space under the perforate floor plate.

4. A brooder including a main casing open at the lower end and provided with interior corner blocks, a floor frame resting removably upon the said corner blocks, flooring supported by the floor frame, a supporting stand formed with a lamp inclosing casing which is open at the top thereof, the lower end of the main casing telescoping over the upper end of the supporting stand until the before mentioned corner blocks rest upon the corners of the supporting stand, and a concave lamp supporting plate interposed between the lower end of the main casing and the supporting stand, said lamp supporting plate being provided with a lamp receiving pocket which projects into the lamp inclosing casing and the concave formation of the lamp supporting plate providing an air space under the flooring of the main casing.

5. A brooder including a main casing provided toward the lower end thereof with interior corner blocks, a floor frame fitted re-

movably within the main casing and resting loosely upon the corner blocks, a perforate floor plate applied to the floor frame and formed with an opening, a ring surrounding 5 the opening and projecting upwardly from the perforate floor plate, fabric flooring supported by the perforate floor plate, a supporting stand formed at the top thereof with a lamp inclosing casing which is open at the 10 upper end, the lower end of the main casing telescoping over the upper end of the supporting stand until the corner blocks rest upon the corners of the supporting stand, and a concave lamp supporting plate resting 15 loosely upon the top of the lamp inclosing casing so as to be held in position by the corner blocks of the main casing, said concave lamp supporting plate being provided with a pendent lamp receiving pocket 20 positioned under the opening of the perforate floor plate and the concave formation of the lamp supporting plate providing a continuous air space under the perforate floor plate.

25 6. A brooder including a main casing provided at the lower end thereof with interior corner blocks and at the upper end thereof with interior cleats, a floor frame fitted removably within the main casing and resting upon the corner blocks, flooring applied to the floor frame, a ceiling frame fitted removably within the upper end of the main casing and resting upon the cleats, a ceiling applied to the ceiling frame, a removable 30 cover fitted to the top of the main casing, and a supporting frame provided with heating means, the lower end of the main casing

35

telescoping over the upper end of the supporting frame until the corner blocks rest upon the corners thereof.

7. A brooder including a main casing provided at the lower end thereof with interior corner blocks and at the upper end thereof with interior cleats, a floor frame fitted removably within the main casing and resting 40 upon the corner blocks, a perforate floor plate applied to the floor frame, a fabric flooring resting upon the perforate floor plate, a ceiling frame fitted removably within the upper end of the main casing and 45 resting upon the cleats, a ceiling applied to the ceiling frame, a cover fitted removably upon the top of the main casing, a supporting frame provided at the upper end thereof with a lamp inclosing casing which opens 50 upwardly, the lower end of the main casing telescoping loosely over the upper end of the lamp inclosing casing until the interior corner blocks rest upon the corners thereof, and a concave lamp supporting plate loosely 55 interposed between the lamp inclosing casing and the main casing, said lamp supporting plate being provided with a pendent lamp receiving pocket and the concave formation of the plate providing a continuous air space under the perforate flooring 60 plate.

In testimony whereof I affix my signature in presence of two witnesses.
